LEVER OPERATED TUFTING MACHINE

William B. Patey, Dalton, Ga., assignor of one-half to Carmack Waterhouse, Dayton, Tenn.

Application May 19, 1938, Serial No. 208,821

8 Claims. (Cl. 112—79)

5 My invention relates to tufting machines for producing tufted chenille bed spreads and the like and more particularly to the type employing a reciprocating looper driven through the cutter blade from the feed dog or other supplemental shaft.

In the prior art, it has been the practice to employ various types of moving loopers for engagement with the loop formed by the needle as it passes through the fabric. These loopers are for the purpose of holding the loop until it can be severed by a cutter. Stewart 1,984,772 shows one form of such attachment for a sewing machine. In that form a looper is pivotally mounted beneath the base plate of the machine, and is actuated by the feed dog shaft in an arcuate path across the plane of the path of the reciprocating needle. A separately actuated blade is carried by the looper for severing the loops. 10 Not only is the structure complicated and flimsy but the looper, moving as it does in an arc, results in uneven clipping of the loops. Another very similar structure is disclosed in the patent to White 2,110,385, who also uses a pivoted looper and a pivoted knife, but the looper is operated through the knife from a central oscillating shaft and finally the patent to Jones 2,096,720 employs a reciprocating looper actuated by the feed dog shaft. The link connecting the blade with the feed dog shaft passes through the blade and projects into a slot in the looper. This necessitates the closing and opening of the blade every time the looper is moved, introduces lost motion of the attachment, 15 increases wear, forces the blade closed while the loop is being engaged by the looper, interferes with the engagement and holding of the looper and prevents the looper from retaining more than one loop at a time. The attachment is also 20 very flimsy.

Applicant with a knowledge of all these defects in and objections to the prior art has for an object of his invention the provision of a tufting machine, including a reciprocating looper driven 25 from the feed dog shaft through the cutter blade.

Applicant has as another object of his invention the provision of a tufting machine employing a reciprocating looper with a blade pivoted thereto to produce even cutting of the loops, and 30 a link joining the blade to the feed dog shaft for actuating both the blade and the looper.

Applicant has as another object of his invention the provision of the looper and blade for a tufting machine which have a minimum movement in carrying out their operations of catching a loop and clipping it, thereby reducing the energy required to operate the machine and the wear incident to its operation.

Applicant has as a further object of his invention the elimination of the central oscillating

shaft, and the use of only one of the feed dog shafts to produce the loop forming and clipping operations.

Other objects and advantages of my invention 5 will appear in the following specifications and the accompanying drawing and the novel features of my invention will be particularly pointed out in the annexed claims.

In the drawing Figure 1 is a fragmental sectional view of a portion of my improved machine. Figure 2 is a plan view of an attachment for my improved machine.

Referring to the drawing in detail, 1 shows a portion of the head of a conventional sewing machine in which is mounted the usual needle bar 2A carrying the reciprocating needle 2. Also projecting downwardly from the head 1 is the usual presser bar 40 to which the presser foot 41 is clamped in the well known manner.

A table 3 is positioned immediately below the 20 presser foot 41 and needle bar 2A. The table 3 carries the ordinary throat plate 4, as disclosed in Stewart *supra*. The work feed means (feed dogs) and the mechanism connecting them to the feed dog shafts are omitted from the drawing for the sake of clarity, for their operation is well known in the art and forms no necessary part of this invention. Beneath the table 3 and adjacent the plate 4 is positioned the frame 7. The frame 7 is mounted upon the usual 25 downwardly projecting extensions through screws 24, 24 that pass through appropriate slots 28 and are controlled by adjusting screws 27 which are locked in any desired position by nuts 26, to vary the position of the looper, to be described hereinafter, with respect to the needle 2.

Mounted to reciprocate within grooves or longitudinal recesses in the frame 7 is a bar 8 carrying a member 17 and secured to such member by screws 16. The member 17 rests within the 40 cut away walls of the frame 7 and is adapted to abut thereagainst to limit the travel of the bar 8. Secured to the upper end of member 17 by means of screws 14 or other appropriate means is a finger or looper having an intermediate cutting edge 18 and a hook end 9.

Pivottally mounted by screw 13 or other appropriate means to the looper or finger is a blade 10 having a cutting edge 11 adapted to co-act with the cutting edge 18 of the looper for severing the loops thereon. Secured to the frame 7 through screw 23 is a block 22, which block must be prevented from movement with respect to frame 7 by a flange or shoulder engagement or interlock with the frame, or by any other appropriate means. 19 designates a link which has an extension 21 that seats in a recess or opening in block 22 and pivots therein. The other end of the link 19 is pivotally connected with the blade 10 intermediate its ends by means of 55 60

screw 28, thus providing a floating pivot for blade 18.

Beneath either side of the bed plate 3, and oscillated in a conventional manner, as indicated in the White patent, supra, are feed dog shafts 5, 6. Clamped on shaft 5 by means of bracket 34 and bolts 35, 36 is crank arm 33. Bridging the space between crank arm 33 and blade 18 is a link 29 which is pivotally secured 10 to both the crank arm and the blade by screws 30, 31.

Carried by the member 17 through screw 15 is a leaf spring 12 which engages blade 18 and bears against it to urge the edge 11 into close cutting 15 engagement with the cutting edge 18 of the looper.

The operation of the machine is somewhat as follows:

The fabric is passed across the bed plate 3 over 20 the throat plate 4, the presser foot 41 is moved to appropriate position and the needle 2 begins its reciprocating movement, driven by the well-known and conventional shaft in the head thereof. The needle passes down through the fabric, carrying the conventional strand of yarn. On the downward stroke, the needle draws the loop and when the needle reaches the lower extremity of its stroke, it begins an upward movement developing slack in the loop. At this point, feed 30 shaft 5 is rotating in a clockwise direction, moving crank arm 33 and link 29 away from the needle, and causing blade 18 to rotate clockwise about its floating pivot 28, opening the blade and moving the looper across the plane of the path of the needle and adjacent to the needle to engage the loop thus formed, and holding it with the hook 9. The needle 2 moves on up out of the fabric drawing the loop tight about the looper. If desired, one or more loops may be 40 formed before clipping, depending upon the relation of the blade to the looper, which may be adjusted or varied.

After the looper has reached the extremity of the movement, the feed dog shaft 5 is reversed 45 and rotates in a counter-clockwise direction, moving the crank arm 33 and link 29 towards the needle and rotating the blade about its floating pivot 28, in a counter-clockwise direction. This forces the looper to move back out of the plane 50 of the reciprocation of the needle and brings edges 11 and 18 of the blade and looper, respectively, into cutting relation. If the looper is designed or adjusted to hold one loop only, then there will be no severing of the loop. However, 55 if this operation be repeated, a loop will be severed each operation thereafter. It will be obvious that it is necessary to employ a floating pivot 28 instead of a stationary pivot in order to permit the pivot point of the blade to travel in an arcuate path as the blade opens and closes to reciprocate the looper.

Having thus described my invention, I claim:

1. A tufting machine of the character described comprising a needle for carrying yarn through a fabric to form a loop, a sliding looper positioned beneath the fabric and adapted to pass between the needle and the loop, a cutter blade pivotally joined to the looper, a floating pivot for said blade, an oscillating shaft, and 65 means joining said blade to said oscillating shaft for actuating the looper through the blade.

2. A tufting machine of the character described comprising a needle for carrying yarn

through a fabric to form a loop, a frame positioned beneath the fabric, a looper slidably mounted in said frame and adapted to pass between the needle and the loop, a blade pivotally joined to the looper, a floating pivot for said 5 blade, and an arm acting on said blade for actuating said looper through said blade.

3. A tufting machine of the character described comprising a needle for carrying yarn through a fabric to form a loop, a frame positioned beneath the fabric, a looper slidably mounted in said frame and adapted to pass between the needle and the loop, a blade pivotally joined to the looper, means carrying a floating pivot for said blade, an oscillating shaft acting 15 on the blade to actuate both the blade and the looper.

4. A tufting machine of the character described comprising a needle for carrying yarn through a fabric to form a loop, a frame positioned beneath the fabric, a looper mounted to reciprocate in the frame and adapted to pass between the needle and loop, a blade pivotally joined to the looper, a movable link pivotally joined to the blade and providing a floating pivot, 20 25 and means acting on said blade for actuating said blade and looper.

5. A tufting machine of the character described comprising a needle for carrying yarn through a fabric to form a loop, a frame positioned beneath the fabric, a looper mounted to slide in the frame and adapted to pass between the needle and loop, a blade pivotally joined to the looper, a movable link pivotally joined to the 30 35 blade and providing a floating pivot, and means acting on said blade for actuating the looper through the blade.

6. A tufting machine of the character described comprising a needle for carrying yarn through a fabric to form a loop, a frame positioned beneath the fabric, a looper positioned to reciprocate in the frame and adapted to pass between the needle and the loop, a blade pivotally joined to the looper, a movable link pivotally joined to the blade and providing a floating pivot, 40 45 an oscillating shaft, and means joining said shaft with said blade to actuate both the blade and the looper.

7. In a tufting attachment, a looper slidably mounted upon the frame and adapted to catch and hold loops of thread from the needle, a cutting edge upon said looper, a blade pivotally joined to said looper for cutting the loops held by said looper, two links jointed to said blade respectively by floating pivots, longitudinally 55 spaced upon said blade, one of said links exerting alternately directed torques upon said blade in opposition to the other link, whereby to reciprocate said looper and to clip said loops.

8. In a tufting attachment, a frame, a looper 60 slidably mounted upon the frame and adapted to catch and hold loops of thread from a needle, a cutting edge upon said looper, a blade pivotally joined to said looper for cutting the loops held by said looper, a central link pivoted on a fixed axis 65 at one end and joined to said blade by a floating pivot at the other end, a lower link joined to said blade by a floating pivot, means for reciprocating said lower link, said means in cooperation with said three pivots reciprocating said blade in cutting engagement with said looper.

WILLIAM B. PATEY.
